F. M. RYAN

ELECTRIC WAVE SIGNALING SYSTEM

Filed Sept. 22, 1925

UNITED STATES PATENT OFFICE.

FRANCIS M. RYAN, OF EAST ORANGE, NEW JERSEY, ASSIGNOR TO WESTERN ELECTRIC COMPANY, INCORPORATED, OF NEW YORK, N. Y., A CORPORATION OF NEW YORK.

ELECTRIC WAVE SIGNALING SYSTEM.

Application filed September 22, 1925. Serial No. 57,809.

This invention relates to electric wave signaling systems, and more particularly to means for controlling the power transmitted by space discharge repeaters.

5 It is well known that when a space discharge tube, which is adjusted to deliver a certain space current, is supplied with alternating current waves, the direct current component or average value of the space current may increase or decrease or, in other words, the average value of the space current may be changed. This change occurs in part by virtue of the fact that the characteristic of the tube is not linear for all values 10 of grid voltage and the character of the change, i. e. increase or decrease depends upon the part of the characteristic curve at which operation is taking place.

A result of this phenomenon, in signaling 20 systems, for example, radio telegraph transmitters as ordinarily adjusted, is that, during the time that signal waves are supplied to the power amplifier, the space current is likely to be much larger than when the 25 waves are interrupted. If the signal waves are controlled by a telegraph key as is done in the so-called CW or continuous wave method of signaling, the plate current of the amplifier will vary in an abrupt manner. The consequence is that changes in the 30 frequency of transmitted waves are produced, and current surges in the space current circuit are set up. These surges cause great changes in the demand upon the 35 source supplying space current to the amplifiers, as well as increase the danger of disruption of insulation.

An object of the invention is to prevent 40 undesired fluctuations in the current supplied to a space discharge tube.

A further object is to maintain the average 45 value of the space current of a space discharge tube substantially constant during changes in the voltage supplied to its input circuit.

Another object is to control signaling 50 waves and a polarizing voltage supplied to a space discharge amplifier to maintain the average space current of the amplifier substantially constant.

A further object is to so control the voltage supplied to the input circuit of a space discharge repeater as to prevent distortion

of signal waves transmitted therethrough caused for example, by a change of frequency.

A still further object is to prevent sudden changes in the impedance of the space path of a space discharge amplifier supplied with interrupted signal waves.

A feature of the invention is a means controlled by a signal source for supplying a polarizing potential to a space discharge amplifier during signaling to maintain the space current of the amplifier at a fixed 65 average value whether signals are transmitted or not.

Another feature is an arrangement co-operating with a source of polarizing potential for controlling the power supplied 70 to a space discharge amplifier and for adjusting the source of polarizing potential to correspond to the power adjustment.

A further feature is an arrangement of space discharge repeaters in tandem and a 75 common control means associated with polarizing potential sources for said repeaters, by the operation of which the impedance of the space paths of the repeaters may be simultaneously varied in the same or opposite senses.

By the invention the broad result is accomplished of controlling the load current of a space discharge device by supplying to its control electrode a suitable voltage to 85 compensate for the effect produced upon the average space current by the application or removal of signal or other alternating current waves. More specifically, the impedance of the tube is adjusted so as to maintain 90 steady and constant the average value of the space current. Means, adapted to remove the compensating voltage when the signal wave voltage is supplied to the space discharge device, is also provided.

A collateral feature of the invention is the combination of a plurality of space discharge repeaters in tandem provided with common control means for increasing the space path impedance of one tube and simultaneously decreasing the impedance of the space path of another tube, so that the average space current of one tandem tube is maintained substantially constant.

In practice, the invention may be embodied in a radio telegraph transmitter includ-

ing a space discharge oscillator adapted to supply high frequency waves to a power space discharge amplifier. A telegraph key is adapted to include or exclude respective resistances in the input circuits of the oscillator and amplifier so that the oscillations may be stopped and started for signaling purposes and, synchronously therewith and in the same order, polarizing voltage 10 is alternately removed from and resupplied to the amplifier control electrode to maintain its average space current constant.

In the figure of the drawing, a radio transmitting system which embodies the invention is illustrated.

A detailed description of the radio transmitter shown in the drawing follows.

This transmitter includes a space discharge oscillator 15 arranged to supply high 20 frequency oscillations to a power space discharge amplifier 16, which is coupled to an antenna 17.

The oscillation generator 15, which is of the general type disclosed in U. S. Patent 25 No. 1,624,537, dated April 12, 1927, comprises a space discharge tube 22, having an input circuit connected to its control electrode and cathode, and an output circuit, connected to its anode and cathode, a feed-back path connected to its anode and control electrode, and a space current supply path also connected to its anode and cathode. The input circuit extends from the control electrode through high frequency choke coil 23, resistance 23', resistance 24, through the secondary winding of transformer 37 to the cathode of tube 22, which is grounded. Resistance 24 is supplied with direct current from a rectifier 25, which is in turn supplied with current through a transformer 26, connected to an alternating current source, herein shown, by way of example, as a generator 27.

Space current is supplied to the tube 22 30 from the rectifier 25. The space current circuit may be traced from the anode through high frequency choke coil 28, inductance 29, high frequency choke coil 30, low frequency choke coil 31, rectifier 25, resistance 24, the winding 37 to the cathode of the tube.

The alternating current output path of tube 22 extends from its anode through choke coil 28, coil 29 shunted by the condensers 35 and 36 to ground, thence to condensers 38 and the cathode of the tube.

Choke coil 31 cooperates with a condenser 34 to suppress undesired variations in the output current from rectifier 25, whereby they are prevented from producing undesired variations in the oscillatory currents. Choke coil 30 prevents the passage of high frequency waves through the rectifier 25 and associated circuits.

Potential across resistance 24 is applied

to the control electrode of tube 22. Resistance 33 is arranged in shunt to the space path of tube 22 and functions to maintain a continuous flow of current from rectifier 25 through resistance 24, regardless of variation in the impedance of the space path of tube 22.

An oscillatory circuit comprising adjustable inductance 29, adjustable condenser 35 and fixed condenser 36, is suitably connected to the electrodes of tube 22. This circuit determines the frequency of oscillations produced by the generator, including the tube 22. The frequency of these oscillations may be varied by adjusting the inductance 29, or variable condenser 35, or both. The alternating potential difference at the terminals of condenser 35 is impressed upon the input electrodes of tube 22 and is adjusted to a suitable value by variation of the condenser 85 capacity.

The cathode of tube 22 is adapted to be heated by current from a secondary winding of transformer 37. The primary winding of this transformer is connected to the generator 27. The mid-point of the secondary winding is connected to ground and its opposite halves are shunted by condensers 38 having equal capacity and low impedance for high frequency waves.

Connected to the condenser 36 of the oscillatory circuit 29, 35, 36 is a coupling path including a condenser 39 in series with resistances 40 and 40'. The waves of potential difference on the plates of condenser 36, produced by the oscillations therein are transmitted to the coupling path and thence to the input circuit of tube 44. This input circuit extends from the control electrode of tube 44 over the path: contact 42 of switch 43, resistance 40', resistance 46, through condensers 38' in shunt to secondary winding of transformer 37' to the cathode.

The resistance 40' is common to the high frequency output circuit of tube 22 and the input circuit of tube 44 of power amplifier 16. The high frequency voltage across this resistance is supplied to the control electrode and cathode of tube 44.

The control electrode and the cathode of tube 44 are also connected by a path including a condenser 45 adapted to prevent the production of parasitic oscillations in the circuits of the amplifier tube. This condenser renders the input path of tube 44 115 capacitive reactive for all frequencies at which detrimental oscillations might otherwise be generated. The function of this condenser is to so shift the phase of the 120 energy supplied from the output to the input circuit of the tube relative to that traversing the input circuit that sustained oscillations are not produced.

The space current circuit of tube 44 may 130 be traced from the anode through inductance

47, choke coils 48 and 49, rectifier 50, resistance 46, secondary winding of transformer 37' to the cathode. The amplifier output circuit is grounded at the terminal of resistance 46 which is connected to rectifier 50.

The filter 51, for suppressing ripples in the current from rectifier 50, is connected in shunt to the rectifier. Choke coil 48 is designed to impede high frequency waves as a means of excluding them from the rectifier 50. Choke coil 49 cooperates with filter 51 in smoothing out variations in the current supplied to the space path of tube 44.

Current for heating the cathode of tube 44 is supplied by means identical with that described in connection with tube 22.

A resonant circuit, including adjustable inductance 47 and an adjustable tuning condenser 52, is connected to the anode and cathode of amplifier 16 and is coupled to the antenna circuit 17 by an adjustable coupling condenser 53. Blocking condenser 54 is provided to exclude direct current from the resonant circuit, and a choke coil 55 serves to confine the direct current potential difference to condenser 54 and to prevent the accumulation of a charge in condenser 53 to thereby permit the use of a condenser which is simple in design and relatively inexpensive to manufacture. This choke coil, however, is of high impedance for high frequency waves and accordingly waves of this frequency at high voltage are impressed across the coupling condenser 53, whereby the energy thereof is supplied to the antenna. The antenna circuit includes a loading inductance 56 in series with a coupling condenser 53, and is connected to ground.

For signaling purposes a telegraph key 66 is included in a series circuit with the winding of a relay 12 and a direct current source 56 represented as a generator.

The switch 43, which by means of its arm 42 serves to adjust the voltage of waves supplied by tube 22 to tube 44, also has a second contact 42' included in circuit with the armature 10 and contact 11 of relay 12. A resistance 13 may be included in this circuit by moving switch 43 to its second contact. Armature 10' and cooperating contact 11' of relay 12 are adapted to short-circuit a large portion of resistance 24, and armature 10 and contact 11 are adapted to short-circuit or connect a low resistance shunt about resistance 46, which is permanently shunted by a fixed condenser 14. The condenser 14 is designed to provide a low impedance path for high frequency waves around resistance 46, to prevent variations of high frequency from producing a large potential across the terminals of the resistance.

The potential drop along resistance 24 when the contact 11' is open is sufficient to maintain the impedance of the space path

of tube 22 so high that oscillations cannot be generated in the system including this tube. Likewise, the drop in potential across resistance 46, which is included in both the input and output circuits of tube 44, is applied to the control electrode of the amplifier, when the armature 10 opens the contact 11, to increase the impedance of the space path of the amplifier. Relay 12 is arranged to cause armature 10 to open its contact with 11 upon operation of the relay, and to simultaneously cause armature 10' to engage its contact 11'.

When resistance 24 is short-circuited by the armature 10 and its associated contact, oscillations are established in the generator 15 and are supplied to the input circuit of the amplifier 44. These oscillations are transmitted through the amplifier, the resonant circuit 47 and 52 and coupling condenser 53 to the antenna 17. Therefore, by operating telegraph key 66, the generation of oscillations in tube 22 may be controlled in accordance with signals.

As already explained, when oscillations are supplied from generator 15 to tube 44, the average value of the space current between the anode and cathode of the tube 44 is ordinarily increased, in part at least, by virtue of the non-linear characteristic of the tube.

In order to maintain the average value of the amplifier space current substantially constant whether key 66 is opened or closed, that is whether oscillations are or are not supplied to the amplifier input circuit, the resistance 46 is adapted to be included in the input circuit of the amplifier and excluded therefrom by the armature 10 and contact 11. The potential supplied by resistance 46 to the control electrode of the amplifier is such as to change the impedance of the space path and reduce the direct current component of the space current to the value which it normally has when no oscillations are supplied to the amplifier.

By virtue of this action abrupt changes in the space current are prevented and the production of surges in space current which cause large changes in the load upon rectifier 50, are prevented.

This invention has been described in connection with a particular embodiment for the purpose of describing its operation but it is to be limited only in accordance with the scope of appended claims.

If tube 44 is so adjusted that when oscillations are supplied to its control electrode the average space current is reduced instead of increased, the proper compensating voltage may be applied by making armature 10 normally out of engagement with contact 11. The armature would then close the contact when relay 12 is operated upon the closure of key 66. By providing resistance 46

of suitable value the compensation may be effected with the difference in operation that resistance 46 applies a negative potential to the control electrode of tube 44 when no waves are supplied thereto but this potential is removed when waves are supplied thereto.

What is claimed is:

1. In combination, a space discharge repeater, a source for supplying high frequency waves to said repeater, means for controlling said waves in accordance with signals, and means affecting the space path impedance of said repeater for maintaining its average space current substantially constant during signaling.

2. In combination, a space discharge repeater having input and output circuits, a source for supplying signal waves to said input circuit, a control means for said source, and a resistance common to said input and output circuits controlled by said means for maintaining the average flow of current in said output circuit substantially constant.

3. A space discharge repeater having an input and an output circuit, means for intermittently supplying waves to said input circuit, the current in said output circuit being affected by said waves, a resistance in said circuits, and means operated in synchronism with a supply of waves to said input circuit to intermittently short-circuit said resistance to compensate for a certain effect of said waves upon said circuit.

4. A space discharge repeater having an input and an output circuit, an impedance network included in both said circuits, a source of signals, and means controlled in accordance with said signals for connecting a shunt path about said network.

5. A plurality of space discharge repeaters in tandem each having an input and an output circuit, separate impedances in said input circuits, a source of signals, and means for alternately shunting said impedances in accordance with signals.

6. A plurality of space discharge repeaters each having an input and an output circuit, separate impedances traversed by direct current included in said input circuits, a source of signals, and a relay connected to said source and controlled by signal impulses therefrom, adapted to alternately shunt one of said impedances and then the other.

7. In combination a plurality of space discharge repeaters each including a cathode, anode and control electrode, means for coupling an anode and cathode of one repeater to the control electrode and cathode of another repeater, a resistance connected to a control electrode of each repeater, said resistances being traversed by direct current, and means for short-circuiting at least a portion of each of said resistances in accordance with signals to maintain the average

space current in one of said repeaters substantially constant.

8. In a radio transmitting system, a space discharge oscillator and a space discharge amplifier coupled in tandem, an input circuit for said oscillator and an input and output circuit for said amplifier, said input circuits including impedance control electrodes, means in said input circuits for impressing a polarizing potential upon said electrodes, a relay controlled by a telegraph key to control the potential impressing means of said oscillator for starting and stopping oscillations and to control the potential impressing means of said amplifier to maintain the average value of its space current substantially fixed.

9. A vacuum tube repeater having an input and an output circuit, an impedance network comprising a resistance and condenser included in both said circuits, a source of signals, and means controlled in accordance with said signals for connecting a short circuit path about said network.

10. In a radio transmitting system an oscillator and an amplifier coupled in tandem by means including a switch and a potentiometer variable by said switch, an input circuit for said amplifier and a resistance included therein, a shunt path for said resistance including a relay armature and contact, and a contact of said switch adapted to change the impedance of said shunt path in accordance with variation of said potentiometer, whereby the potential supplied to the input circuit of said amplifier may be adjusted.

11. In combination a space discharge oscillator and a space discharge repeater each having an input and a space current circuit, a resistance included in each of said input circuits, one of said resistances being included also in the space current circuit of said repeater, and means for intermittently and alternately shunting a portion of said resistances to vary the impedance of said oscillator for controlling the generation of oscillations and to maintain the impedance of the space path of said amplifier substantially constant.

12. The method of operating a space discharge repeater to maintain a constant average space current which comprises, impressing upon the control electrode of said repeater, waves to be amplified and simultaneously impressing thereon a steady polarizing voltage of such magnitude as to compensate for the change in the average control electrode potential occasioned by the waves to be amplified.

In witness whereof, I have hereunto subscribed my name this 3rd day of September A. D., 1925.

FRANCIS M. RYAN.
